UNITED STATES PATENT OFFICE.

MITCHEL E. HADAD, OF BROOKLYN, NEW YORK, ASSIGNOR TO HENRY HADAD COMPANY, INC., OF NEW YORK, N. Y., A CORPORATION OF NEW YORK.

DESIGN FOR A TEXTILE FABRIC OR SIMILAR ARTICLE OF MANUFACTURE.

Application filed March 20, 1928. Serial No. 25,925. Term of patent 8½ years.

To all whom it may concern:

Be it known that I, MITCHEL E. HADAD, a citizen of the United States, and a resident of Brooklyn, county of Kings, and State of New York, have invented a new, original, and ornamental Design for a Textile Fabric or Similar Article of Manufacture, of which the following is a specification, reference being had to the accompanying drawing, forming part thereof, wherein the figure is a plan view of a piece of cloth showing the design.

I claim:

The ornamental design for a textile fabric or similar article of manufacture substantially as shown.

MITCHEL E. HADAD.
